MACHINE FOR POLISHING BLADES

John Oliver Creek, Brampton, Ontario, Canada,
assignor to A. V. Roe Canada Limited, Malton,
Ontario, Canada, a corporation.

Application December 20, 1950, Serial No. 201,743.

19 Claims. (Cl. 51—19)

1

This invention relates to a machine for polishing blades and more particularly to a machine for giving a fine precision polish to blades for gas turbine engines.

Various methods and apparatuses have been proposed from time to time for polishing articles, consisting basically in mounting the articles on a carrier and rotating the carrier to move the articles through an abrasive or polishing material in a liquid or granular suspension. Whilst such a process can be used for polishing many articles, it cannot be applied directly to the polishing of blades for gas turbine engines. These blades have to be made to a high order of accuracy and require a very high degree of surface finish which must be applied after the completion of all forming operations. If a blade of this kind were passed in the usual manner through an abrasive or polishing medium sufficiently to produce the required high degree of surface finish, an inadmissibly large alteration in the profile of the blade would occur, due to uneven action of the polishing medium. This uneven action is pronounced in machines in which a circular motion is imparted to the polishing medium, setting up centrifugal forces which tend to compact the medium.

Hitherto, the blades of gas turbine engines have been finished by hand-buffing processes, which are slow and expensive and which also entail some risk of damage to the blades, particularly at the trailing edges.

The main object of the present invention is, therefore, to provide a machine in which a plurality of blades may be polished simultaneously to a high surface finish without materially changing their profile, thereby saving time and avoiding the risks attendant upon hand-buffing processes.

Another object of the invention is to provide a polishing machine having structural features whereby a more uniform density is obtained throughout the depth of the polishing medium, thereby ensuring a more even polishing action on the blades.

The invention will be more readily understood by reference to the following description and the accompanying drawings in which like reference characters designate corresponding parts throughout the several views, and in which:

Fig. 1 is a broken-away fragmentary elevation of a polishing machine constructed in accordance with the invention;

Fig. 2 is a broken-away plan of the machine;

Fig. 3 is a broken-away elevation to an enlarged scale of the upper half of the machine;

Fig. 4 is a broken-away perspective of a por-

2

tion of the machine viewed in the general direction of the arrow A in Fig. 3;

Fig. 5 is a schematic view of the mechanism which imparts an oscillatory rotation to the workspindles, and the controls therefor.

A machine constructed in accordance with this invention comprises a hollow base 1 supporting a hollow column 2 to the upper end of which is clamped a two-armed bracket 3. At 10 the end of a fork of the arm 3a is journalled a rotatable workspindle carrier 4 (Fig. 3).

On the carrier are mounted several workspindles 5 each of which supports a holder 6 in which is held a blade B which is to be polished; 15 the workspindles are mounted for rotation about their longitudinal axes, means being provided to impart to the workspindles a limited amount of rotation. Rotatably mounted on the lower part of the column 2 is a spider 7 comprising four 20 radial arms which each support in a horizontal position, an annular trough 8 for the polishing medium; the troughs are adapted to be selectively brought into registration with the carrier 4 and then raised upwardly into operative position 25 so that the blades supported by the workspindles dip into the polishing medium. To hold each trough 8 in position when brought into registration with the carrier 4, leaf springs 9 are mounted on the underside of the respective arms of the 30 spider 7; these springs are adapted to snap into a recess in a block 10 provided on the base of the machine.

At the outer end of each arm of the spider 7 are provided a pair of bushed bores 11 in which 35 a trough support tube 12 is slidably mounted; the upper end of each support tube fits into the hub 13 of a trough support plate 14. Located within the hollow base of the machine at a position immediately underneath the axis of the 40 carrier 4 is an airjack 15, the piston rod 16 of which extends through a suitable aperture provided in the top plate of the base and is adapted to engage the lower end of the support tube 12 of whatever trough is in registration with the 45 carrier 4; when the airjack is actuated, its piston elevates the trough into cooperative position with the carrier.

Each trough 8 is intended to contain a different grade of granular polishing medium, such as 50 wheat, flax seed, rice, sawdust or granulated cork, to which may be added as is well known in the art a polishing or abrasive compound such as silicon carbide or jeweller's rouge; wax may also be added as a bonding agent.

55 At the lower end of each support tube 12 is provided a female airline connector 17 and at the upper end of the piston rod 16 is a male air-

line connector 18 adapted to register with the female connector 17, the male connector being connected by a flexible airline 19 to a source of compressed air. The compressed air passes through the two connectors and flows through the support tube 12 of the trough 8 in use, and is distributed by six equally spaced radial pipes 20 (Fig. 3) connecting the interior of the support tube to a manifold 21 provided at the bottom of the trough. From the manifold 21 the compressed air is introduced into the polishing medium through a series of apertures 22 in the bottom of the trough to elevate the particles of the polishing medium thus counteracting the increasing pressure or "head" towards the bottom of the trough and providing for a more uniform density throughout the mass of the polishing medium.

When the airjack 15 is actuated to lower a trough 8 which has previously been brought into cooperative registration with the carrier 4, the said trough descends until the hub of its support plate 14 rests on the upper bushed bore 11, in which position the trough is clear of the blades B. In this position, the polished blades can be replaced by others which are to be processed. The piston rod 16 of the airjack 15 is of course lowered to a position such that the male connector 18 is clear of the female connector 17, thereby permitting the spider 7 to be rotated to bring into registration with the carrier 4 another trough 8.

Baffles 23, which are inclined upwardly in the sense of rotation of the carrier 4, are arranged at spaced intervals around the walls of each trough 8. The polishing material displaced by the passage of the blades B through the trough is directed upwardly by the baffles, thus relieving the loads on the tips of the blades which would otherwise occur due to the density gradient or increasing pressure of the polishing medium towards the bottom of the trough. These baffles not only cause a more uniform density throughout the mass of polishing medium but also tend to direct the polishing medium upwardly upon the roots B' (Fig. 4) of the blades.

So as to facilitate replacing worn baffles 23 and also in order to protect the inner sidewalls of the trough 8 from the wearing effect of the polishing medium, the said walls are lined with annular strips of metal, to which the baffles are secured. Also, the lower ends of the holders 6 are faced with rubber to protect them from abrasion.

As previously mentioned, clamped around the upper end of the column 2 is the bracket 3. At the outer end of the lower fork of the arm 3a is a hub 24 which provides a bearing in which is rotatably mounted the carrier 4. For this purpose a pulley sleeve 25 is journaled within the hub 24 by means of radial and thrust ball bearings. To the upper end of the pulley sleeve 25 is keyed a pulley 26 which is coupled by V-belts to a pulley 27 keyed at the upper end of a drive shaft 28 journaled within the column 2 and having at its lower end a worm wheel 29 driven through a worm, pulley, and V-belt assembly 30 by a change speed unit 31 incorporating an electric driving motor. At the lower end of the pulley sleeve 25 is a flange to which is secured to the workspindle carrier 4. Thus, when the motor is energized it will cause rotation of the workspindle carrier. Above the carrier 4 and around its sides is a fixed hood 32, secured to the lower end of the hub 24.

Around the bottom periphery of the hood is a rubber sealing ring 33 which engages a similar sealing ring provided on the upper outer periphery of the trough 8 brought into registration therewith.

The workspindles 5 which are operatively arranged in pairs are journaled in ballbearings mounted in suitable bores formed in upper and lower internal flanges 34 and 35 of the carrier 4 (see Figs. 3 and 4). Secured to the lower flange 35 intermediate the workspindles of each pair is a pedestal 36, and on each pedestal is journaled a horizontally disposed stub shaft 37 to which is centrally keyed a driving pinion 38 and at each end of which are keyed bevel gears 39. The bevel gears 39 mesh respectively with bevel gears 40 which are mounted on the workspindles 5 of the pair. As will be apparent particularly from Fig. 4, if pinion 38 is rotated, the two workspindles of the pair will rotate in opposite directions relative to each other.

A shaft 41 is slidably mounted in the bore of the pulley sleeve 25, and at the upper end of the shaft is secured a flanged sleeve 42, the flange of which lies between a pair of thrust bearings of a coupling 43 from the top of which extends a screw-threaded shank. At the lower end of the shaft 41 is keyed a rack wheel 44, on the periphery of which are racks 45 which mesh with corresponding pinions 38. It will be apparent that if the shaft 41 is reciprocated, the racks 45 will rotate the corresponding pinions 38 to and fro thereby causing oscillation of the blades supported by the workspindles.

At the end of the upper fork of the arm 3a is provided a fixture 46 to the upper face of which is secured an air-operated power cylinder 47 and to the lower face of which is secured a hydraulic cylinder 48, which exercises a control on the operation of the power cylinder; the two cylinders are co-axial with the shaft 41. In the power cylinder and in the hydraulic cylinder are provided pistons, the piston rods of which are coupled to each other; also, the piston rod of the hydraulic cylinder is connected to the screw threaded shank of the coupling 43.

Secured to the coupling 43 is a horizontally extending yoke member 49, the outer end of which is forked to embrace a vertically disposed slide-way 50 extending from the arm 3a; the yoke member 49 permits the coupling to be moved vertically by the action of the piston in the power cylinder 47 but prevents rotation of the coupling 43. It should be noted that the coupling 43 enables the shaft 41 to rotate without transmitting its rotation to the two piston rods.

The workspindles 5 are oscillated by the reciprocation of the shaft 41 as hereinafter described with particular reference to Fig. 5. Ports at opposite ends of the power cylinder 47 are connected by suitable air lines to ports 51 of a distribution valve 52 secured to the arm 3a. Air is supplied to the distribution valve by an airline 53 which passes through the column 2 into the hollow base and is connected to a suitable source of compressed air (not shown).

The distribution valve 52 is of the type containing a selectively displaceable spool, which, depending on its position, distributes compressed air supplied from the airline 53 to one of the ports 51 and connects the other port 51 to atmosphere through one of the outlets 54. Both ends of the spool are under pressure due to the provision of narrow passages 53a in the body of the valve, and movement of the spool is caused by bleeding air

from either of the ports 55 at opposite ends of the valve; the ports 55 are connected by airlines to bleed valves 56 and 56a mounted at opposite ends of the slideway 57 of a control fixture 58. The control fixture is secured to the fixed hub 24 (see Fig. 3) and on its slideway 57 is slidably mounted a carriage 59. On the carriage is a cam member 60 having adjustable bolts 61 which provide abutment surfaces adapted to contact the plungers of the bleed valves 56 and 56a to cause reversal of the air supply to the power cylinder 47. The cam member also includes a cam surface 62 with which cooperates a follower wheel 63 mounted on the end of the spring-pressed spool spindle 64 of a flow control valve 65 for the hydraulic cylinder 48. The flow control valve is secured to an extension of the control fixture 58.

Ports at either end of the hydraulic cylinder 48 are connected to the ports of the flow control valve 65 and thus a closed circuit is provided for the oil with which the system is filled. When the spring-pressed spindle 64 of the valve 65 is displaced by the cam surface 62 to the position shown in Fig. 5, the spool 66 on the spindle 64 clears the port 67 and thus the oil in the system of the hydraulic cylinder can flow freely, permitting the power cylinder 47 to impart a rapid motion to the shaft 41 which imparts a correspondingly rapid motion to each workspindle 5 about its own axis, as previously described. When, however, the follower wheel 63 is not displaced by the cam surface 62, the spool 66 closes the port 67 and the oil is constrained to flow through a metering orifice 68 regulated by an adjustable needle valve 69, and thus the speed of displacement of the shaft 41 by the power cylinder 47 can be controlled, thereby limiting the angular velocity of the rotary motion imparted to the workspindles 5.

The carriage 59 of the control fixture 58 is connected by a push-pull cable 70 to the yoke member 49, the casing 71 of the cable being secured to the arm 3a; thus the carriage 59 moves in correspondence with the movements of the shaft 41. The stroke of the piston of the power cylinder 47, and hence the range of angular displacement of the workspindles 5, is dependent on the design of the cam member 60 and more particularly on the adjustment of the bolts 61 which by actuating the bleed valves 56 and 56a control the stroke of the piston of the power cylinder 47. Furthermore, the angular velocity of the workspindles 5 is normally determined by the adjustment of the needle valve 69, except over the range of angular displacement coincident with the engagement of the cam surface 62 with the follower wheel 63; the angular velocity over this range and the period when it occurs in the cycle of operation of the machine is of course determined by the configuration of the cam surface 62.

It should be mentioned that for the practical operation of the machine, suitable quick release holders 6 in which the blades are held should be used, but such chucks will not be described as they do not per se form part of the invention. The holders are conveniently inserted and held in the workspindles 5 by bayonet-type couplings, which also permit their easy withdrawal therefrom.

Operation

It is first necessary to construct a cam member 60 so designed that there will be imparted to each blade during its passage through the polishing medium, a predetermined range of angular displacement about its longitudinal axis so as to

produce the desired polishing action for the particular shape of blade being treated. The cam member 60 is mounted on the carriage 59 and the blades to be polished are mounted in the holders 6 which in turn are inserted in the workspindles 5.

Referring to Fig. 5, the various components of the control system are preferably set in such a manner that at the commencement of the operation the cam member 60 is at the right-hand side of its stroke and has actuated the bleed valve 56a to cause the spool of the distribution valve 52 to move to the position opposite to that shown in Fig. 5, at which position the upper end of the power cylinder 47 is connected to the compressed air supply and the piston of this cylinder is about to start its down stroke. The rack wheel 44 is, therefore, in its upper position and the blades to be polished have a predetermined angle of incidence; for instance, as shown in Fig. 2, alternate blades have an angle of incidence of approximately +30° and the other blades have an angle of incidence of approximately -30°.

A trough 8 containing a coarse grade of polishing medium is then brought into registration with the carrier 4 and raised into operative position by actuation of the air-jack 15. Next, the drive of the change speed unit 31 is started, to cause rotation of the carrier 4 and thus pass the blades in a continuous path through the polishing medium; the compressed air supply to the manifold 21 is turned on, thereby elevating the particles of polishing medium, and the compressed air supply to the distribution valve 52 is also turned on to cause a progressive change of angular displacement of the blades B about their longitudinal axes during their travel through the polishing medium. The rate of change of this angular displacement is determined by the setting of the needle valve 69 since at this stage the cam surface 62 is not in contact with the follower wheel 63 of the flow control valve 65; this change of angular displacement is continued until each blade reaches a limiting angle of incidence, for example, -30° in the case of blades which were initially at an angle of incidence of +30°.

The essence of this invention is that each blade is moved in a continuous path through a polishing medium of substantially uniform density while the blade is given an angular rotation about its longitudinal axis between two angles of incidence appropriate to the aerofoil shape of the blade. The limiting angles of incidence may also vary according to the polishing medium used and the material of which the blade is made, though these considerations have perhaps a greater influence upon the choice of speed with which the blade is passed through the medium or with which the angle of incidence is changed, or both. Furthermore the limiting angular displacements need not be symmetrically disposed about the path of the blade as in the example described, in which the angle of incidence varies between +30° and -30°; the range might lie between +5° and -50°, or between 0° and +30°. As stated, the choice of these limits depends primarily upon the aerofoil characteristics of the blade to be polished; for example the limits are determined largely by the stalling properties of the aerofoil, i. e., the shape of the aerofoil and the consequential angle at which a medium through which the aerofoil is passing tends to depart from the contour of the aerofoil; I have found by experiments that the limiting angles 70 of incidence of the blade usually should not ex-

ceed the stalling angles, but occasionally they may be exceeded slightly to favour one or other of the blade surfaces. In all cases the initial and limiting angles of incidence are within 55° of 0 angle of incidence, and the difference between the said initial and limiting angles is less than 70°.

The speed of rotation of the blade about its longitudinal axis is relatively slow. The polishing action is achieved by the passage of the blade through the polishing medium in such a way that the relative movement between the blade and the medium is similar to the relative movement between the blade and the working fluid of the gas turbine engine in which the blade will eventually be installed. In other words the flow of the polishing medium past the blade is analogous to aerodynamic flow, wherein the relative movement between each surface of the aerofoil and the surrounding medium is in the same direction on both sides of the blade, that is from the leading edge to the trailing edge. The relatively slow rotation of the blade about its longitudinal axis produces no more than a change of incidence or attitude, as hereinbefore described, and does not contribute directly to the polishing action of the medium upon the blade. It will be understood therefore that the polishing effect of the machine is ideally suited to aerofoil shapes or to any blade-like articles having a pronounced finesse ratio.

The polishing process may be accelerated by passing the blades through the polishing medium firstly in one direction and secondly in the reverse direction and it is of advantage if this reversal can be effected automatically. In the machine described, therefore, after a blade has undergone a rotation about its longitudinal axis from an angle of incidence of +30° to an angle of incidence of -30°, at a uniform speed, whilst the carrier 4 has made several complete revolutions, the cam surface 62 of the cam member 60 comes into contact with the follower wheel 63 and causes displacement of the spool spindle 64 to open the port 67. The hydraulic cylinder 48 which was theretofore providing a damping action on the movement of the piston in the power cylinder 47 therefore virtually becomes ineffective, and consequently the power cylinder will suddenly force the piston rods and the rack wheel 44 downwardly at an increased velocity with a consequent increase in the angular velocity of each blade about its longitudinal axis. This rapid transition occurs over an angle of, for example, 120°, that is until each blade is displaced approximately 180° from its initial position, whereupon the follower wheel 63 will leave the cam surface 62 of the cam member 60 which is moving towards the left-hand side in unison with the rack wheel shaft 41. If desired, the speed of rotation of the carrier 4 may be reduced or its rotation may be arrested during this operation, to avoid damage to the blades as they pass through high angles of incidence to the polishing medium. The opposite edge of each blade is now meeting the polishing medium and since the follower wheel 63 is no longer in contact with the cam surface 62, the angular displacement of each blade is changed at its original speed (under the control of the needle valve 69) until each blade has been displaced through a further angle of 60°, whereupon the left-hand side adjustment bolt 61 of the cam member 60 actuates the bleed valve 56 and initiates the return stroke of the piston of the power cylinder

47 and hence initiates an angular movement of the blades in the reverse direction. The above described cycle can be repeated as often as required. It will be understood that, in this example, the total angular travel of the work-spindles 5 is 240°, comprising the first range (60°) of the polishing operation, the transition range (120°), and the second range (60°) of the polishing operation; the cycle does not involve a complete 360° rotation of the blades.

Since the speed of rotation of the carrier 4 is controlled independently of the oscillatory rotation imparted to the blades, and since this oscillatory rotation can be of many different characteristics dependent on the design of the cam member 60, a wide range of polishing actions is available to suit the requirements of diverse forms of blade constructions.

It will be appreciated that by rotating alternate blades about their longitudinal axes in opposite directions in accordance with this invention, the alternate blades displace the polishing medium during their passage therethrough in opposite directions so that the polishing medium is not compacted on one side of the trough as would occur if all the blades had the same angle of incidence. Moreover, since the trough 4 remains stationary throughout the polishing operation, the polishing medium is not compacted against the outer wall of the trough by centrifugal forces as occurs in polishing machine construction in which the container of polishing medium is rotated.

It is thought that the construction and use of the invention will be apparent from the above description of the various parts and their purpose. It is to be understood that the form of the invention herewith shown and described is to be taken as a preferred example of the same and that various changes in the shape, size and arrangement of parts may be resorted to, without departing from the spirit of the invention or the scope of the subjoined claims.

What I claim as my invention is:

1. A machine for polishing blades, comprising a carrier, a container for a polishing medium disposed adjacent the carrier, the carrier and container being mounted for movement relative to each other, means mounted on the carrier for holding the blades in the polishing medium, means for translating the carrier and container relative to each other to pass the blades in a continuous path through the polishing medium, means to render the density gradient of the polishing medium immediately prior to contact with each blade no greater than the density gradient of the polishing medium when at rest and means for changing, during the translation of the carrier relative to the container, the angles of the holding means relative to the direction of said translation to vary the angles of incidence of the blades between initial angles and limiting angles.

2. A machine for polishing blades, comprising a carrier, a container for a polishing medium disposed adjacent the carrier, the carrier and container being mounted for movement relative to each other, means mounted on the carrier for holding the blades in the polishing medium, means for translating the carrier and container relative to each other to pass the blades in a continuous path through the polishing medium, means to render the density gradient of the polishing medium immediately prior to contact with each blade no greater than the density

gradient of the polishing medium when at rest and means for changing, during the translation of the carrier relative to the container, the angles of the holding means relative to the direction of said translation, to vary the angles of incidence of the blades between initial angles and limiting angles, the initial and limiting angles of incidence being within 55° of 0 angle of incidence and the difference between the said initial and limiting angles being less than 70°.

3. A machine for polishing blades of aerofoil shape, comprising a carrier, a container for a polishing medium disposed underneath the carrier, the carrier and container being mounted for movement relative to each other, a pair of spindles rotatably mounted on the carrier for suspending the blades in the polishing medium, means for translating the carrier and container relative to each other to pass the blades in a continuous path through the polishing medium, and means for progressively rotating the two spindles in mutually opposite senses during the translation of the carrier relative to the container to vary the angle of incidence of each blade.

4. A machine for polishing blades comprising a stationary frame, a carrier mounted on the frame for rotation about a substantially vertical axis, a plurality of containers for polishing mediums selectively positionable in registration with the carrier, means for raising a registering container into co-operative position with the carrier, spindles rotatably mounted on the carrier for suspending the blades in the polishing medium contained in the container co-operatively positioned with the carrier, means for rotating the carrier to pass the blades in a continuous path through the said polishing medium and means for progressively rotating the spindles during the rotation of the carrier to vary the angle of incidence of each blade between an initial angle and a limiting angle.

5. A machine for polishing blades of aerofoil shape, comprising a stationary frame, a carrier mounted on the frame for rotation about a substantially vertical axis, a container for a polishing medium disposed underneath the carrier, spindles rotatably mounted on the carrier for suspending the blades in the polishing medium, means for rotating the carrier to pass the blades in a continuous path through the polishing medium, means for progressively rotating the spindles during the rotation of the carrier to vary the angle of incidence of each blade between an initial angle and a limiting angle, and means in the container to elevate the particles of the polishing medium as the blades pass therethrough.

6. A machine for polishing blades of aerofoil shape, comprising a stationary frame, a carrier mounted on the frame for rotation about a substantially vertical axis, a container for a polishing medium disposed underneath the carrier, spindles rotatably mounted on the carrier for suspending the blades in the polishing medium, means for rotating the carrier to pass the blades in a continuous path through the polishing medium, means for progressively rotating the spindles during the rotation of the carrier to vary the angle of incidence of each blade between an initial angle and a limiting angle, and air jets extending upwardly from the bottom of the container to elevate the particles of the polishing medium and provide a more uniform density throughout the mass of the said medium.

7. A machine for polishing blades of aerofoil shape, comprising a stationary frame, a carrier

mounted on the frame for rotation about a substantially vertical axis, an annular trough for a polishing medium disposed underneath the carrier co-axially therewith, a perforated air manifold at the bottom of the trough, a source of compressed air connected to the manifold for ejecting air through the apertures and into the polishing medium to elevate the particles of the medium and provide a more uniform density throughout the mass of the said medium, spindles rotatably mounted on the carrier for suspending the blades in the polishing medium, means for rotating the carrier to pass the blades in a continuous path through the polishing medium, and means for progressively rotating the spindles during the rotation of the carrier to vary the angle of incidence of each blade between an initial angle and a limiting angle.

8. A machine for polishing blades, comprising a stationary frame, a carrier mounted on the frame for rotation about a substantially vertical axis, a multi-armed spider mounted on the frame for rotation about another substantially vertical axis, a sleeve at the end of each spider arm, a hollow shaft slidably mounted in each sleeve, containers for polishing mediums supported at the upper ends of the respective shafts, a perforated manifold at the bottom of each container and connected to the passage in the hollow shaft,

30 the containers being selectively positionable in registration with the carrier, means engaging with the lower end of a hollow shaft supporting a container positioned in registration with the carrier for raising the said container into co-operative position with the carrier, a coupling at the upper end of the container raising means connected to a source of compressed air and connecting to the source of compressed air the hollow shaft in engagement with the container raising means, the compressed air being thus conveyed to the manifold and ejected through the apertures therein into the polishing medium to elevate the particles of the medium and provide a more uniform density throughout the mass of the said medium, spindles rotatably mounted on the carrier for suspending the blades in the container co-operatively positioned with the carrier,

35 means for rotating the carrier to pass the blades in a continuous path through the said polishing medium, and means for progressively rotating the spindles during the rotation of the carrier to vary the angle of incidence of each blade between an initial angle and a limiting angle.

9. A machine for polishing blades of aerofoil design comprising a stationary frame, a carrier mounted on the frame for rotation about a substantially vertical axis, an annular trough for a polishing medium disposed underneath the carrier co-axially therewith, spindles rotatably mounted on the carrier for suspending the blades in the polishing medium, means for rotating the carrier to pass the blades in a continuous path through the polishing medium, baffles on the sidewalls of the trough, the said baffles being inclined upwardly in the sense of rotation of the carrier, and means for progressively rotating the spindles during the rotation of the carrier to vary the angle of incidence of each blade between an initial angle and a limiting angle, the baffles elevating the particles of the polishing medium which are projected thereagainst by the blades as they pass through the polishing medium.

10. A machine for polishing blades of aerofoil design comprising a stationary frame, a carrier mounted on the frame for rotation about a sub-

stantially vertical axis, a stationary container for a polishing medium disposed underneath the carrier, spindles rotatably mounted on the carrier for suspending the blades in the polishing medium, means for rotating the carrier to pass the blades in a continuous path through the polishing medium, and means for progressively rotating the spindles during the rotation of the carrier to vary the angle of incidence of each blade in three stages, namely from an initial angle to a first limiting angle at a low rate of change, then from the said limiting angle to another limiting angle at a high rate of change, and finally from the said other limiting angle to a final angle at a low rate of change.

11. A machine for polishing blades of aerofoil design comprising a stationary frame, a carrier mounted on the frame for rotation about a substantially vertical axis, a stationary container for a polishing medium disposed underneath the carrier, spindles rotatably mounted on the carrier for suspending the blades in the polishing medium, means for rotating the carrier to pass the blades in a continuous path through the polishing medium, and means for progressively rotating the spindles during the rotation of the carrier, and a control to control the velocity of the power means in three stages, namely a first stage at which the blades are rotated from an initial angle to a first limiting angle at a low rate of change, then from the said limiting angle to another limiting angle at a high rate of change, and finally from the said other limiting angle to a final angle at a low rate of change.

12. A machine for polishing blades of aerofoil design comprising a stationary frame, a carrier mounted on the frame for rotation about a substantially vertical axis, a container for a polishing medium disposed underneath the carrier coaxially therewith, spindles rotatably mounted on the carrier for suspending the blades in the polishing medium, rack means adjacent the carrier and mounted for rotation therewith, the said rack means being reciprocatable in a direction parallel to the axis of rotation of the rotation of the carrier, means coupling the rack means to the spindles whereby reciprocation of the rack means causes to and fro rotation of the spindles, and a power and control mechanism for the rack means for progressively rotating the spindles during the rotation of the carrier to vary the angles of incidence of the blades between an initial angle and a limiting angle.

13. A machine for polishing blades of aerofoil design comprising a stationary frame, a carrier mounted on the frame for rotation about a substantially vertical axis, a container for a polishing medium disposed underneath the carrier coaxially therewith, spindles rotatably mounted on the carrier for suspending the blades in the polishing medium, the said spindles being rotatable in pairs, a bevel gear on each spindle, pillars mounted on the carrier between the spindles of each pair, a horizontally disposed rotatable shaft supported by each pillar and having at opposite ends bevel gears which engage respectively with the bevel gears of the spindles of the pair, a pinion on each of the said shafts, a rack member adjacent the carrier and mounted on the frame for rotation with the carrier, the said rack member being reciprocatable in a direction parallel to the axis of rotation of the carrier, racks on the rack member engaging with the respective pinions, and a power and control mechanism for controllably translating the rack

member to rotate progressively the spindles during the rotation of the carrier to vary the angles of incidence of the blades between an initial angle and a limiting angle.

14. A machine for polishing blades of aerofoil design comprising a stationary frame having a vertically disposed bearing, a sleeve journaled in the bearing, power means coupled to the upper end of the sleeve to rotate it, a disc providing a workspindle carrier secured to the lower end of the sleeve, an annular trough for a polishing medium disposed below the lower face of the disc co-axially therewith, a plurality of pillars mounted on the top face of the carrier and positioned above the trough, workspindles mounted for rotation on the carrier at opposite sides of each pillar, the workspindles passing through the carrier and being adapted to support at their lower ends blades which extend into the polishing medium, a bevel gear at the other end of each workspindle, a horizontally disposed shaft journaled in each pillar and having at opposite ends bevel gears which engage respectively with the gears of the workspindles at opposite sides of the pillar, a pinion on each shaft, a power shaft translatable mounted in the sleeve and extending therethrough, a rack member secured to the lower end of the power shaft and disposed above the top face of the carrier, racks on the rack member engaging with the respective pinions, and a power and control mechanism coupled to the upper end of the power shaft for controllably translating the power shaft to progressively rotate the spindles during the rotation of the carrier, thereby varying the angles of incidence of the blades.

15. In a machine tool having a rotatable workspindle carrier, workspindles rotatably mounted on the carrier, and reciprocating means coupled to the workspindles to cause to and fro rotation of the workspindles, a power and control system for the reciprocating means, comprising a power jack including a piston reciprocably mounted within a cylinder, a second jack including a piston reciprocatably mounted within a cylinder, the pistons of the two jacks being serially connected to the reciprocating means, a source of fluid pressure, a valve having an inlet connected to the source and outlets connected to the cylinder of the power jack at opposite sides of the piston therein, a two position selector in the valve to selectively connect the inlet to the outlets thereby enabling the fluid pressure to urge the piston of the power jack in one sense or in the opposite sense, means actuated by the pistons when they reach the end of their stroke in one sense to move the selector from one position to the other position to enable the fluid under pressure to urge the piston of the power jack in the opposite sense, a closed fluid circuit connected to the cylinder of the second jack at opposite sides of the piston therein, a restricted passage in the circuit to impede the flow of fluid in the circuit thereby retarding the movement of the pistons, a valve in parallel with the restricted passage selectively adjustable to open and closed positions, the last mentioned valve when adjusted to open position allowing the fluid to flow freely in the circuit thereby enabling the pistons to move at a high velocity under the urging of the fluid flow system.

16. In a machine tool having a rotatable workspindle carrier, workspindles rotatably mounted on the carrier, and reciprocating means coupled to the workspindles to cause to and fro rotation

of the workspindles, a power and control circuit for the reciprocating means, comprising a power jack including a piston reciprocatably mounted within a cylinder, a second jack including a piston reciprocatably mounted within a cylinder, the pistons of the two jacks being serially connected to the reciprocating means, a source of fluid pressure, a valve having an inlet connected to the source and outlets connected to the cylinder of the power jack at opposite sides of the piston therein, a two position selector in the valve to selectively connect the inlet to the outlets thereby enabling the fluid pressure to urge the piston of the power jack in one sense or in the opposite sense, means actuated by the pistons when they reach the end of their stroke in one sense to move the selector from one position to the other position to enable the fluid under pressure to urge the piston of the power jack in the opposite sense, a closed fluid circuit connected to the cylinder of the second jack at opposite sides of the piston therein, a restricted passage in the circuit to impede the flow of fluid in the circuit thereby retarding the movement of the pistons, a valve in parallel with the restricted passage, an element in the said valve positionable to valve opening and valve closing position, the said valve allowing the fluid to flow freely in the circuit thereby enabling the pistons to move at a high velocity under the urging of the fluid flow system when the element is adjusted to valve opening position, a cam for selectively positioning the valve element, and means linking the pistons and the cam to position the cam in correspondence with the position of the pistons.

17. A machine for polishing blades, comprising a carrier, a container for a polishing medium disposed adjacent the carrier, the carrier and container being mounted for movement relative to each other, means mounted on the carrier for holding the blades in the polishing medium, means for translating the carrier and container relative to each other to pass the blades in a continuous path through the polishing medium, means to render the density gradient of the polishing medium immediately prior to contact with each blade no greater than the density gradient of the polishing medium when at rest, and means for changing, during the translation of the carrier relative to the container, the angles of the holding means relative to the direction of said translation to vary the angles of incidence of the blades between initial angles and limiting angles at such a speed relative to the speed of passage of the blades through the polishing medium that the relative movement between the medium and one surface of the blade is always in the same direction as the relative movement between the medium and the opposite surface of the blade.

18. A machine for polishing blades, comprising a carrier, a container for a polishing medium

disposed adjacent the carrier, the carrier and container being mounted for movement relative to each other, means mounted on the carrier for holding the blades in the polishing medium, 5 means for translating the carrier and container relative to each other to pass the blades in a continuous path through the polishing medium, means to render the density gradient of the polishing medium immediately prior to contact 10 with each blade no greater than the density gradient of the polishing medium when at rest, and means for changing, during the translation of the carrier relative to the container, the angles of the holding means relative to the direction of 15 said translation to vary the angles of incidence of the blades between initial angles and limiting angles at such a speed relative to the speed of passage of the blades through the polishing medium that the relative movement between the 20 medium and one surface of the blade is always in the same direction as the relative movement between the medium and the opposite surface of the blade, the initial and limiting angles of incidence being within 55° of 0 angle of incidence 25 and the difference between the said initial and limiting angles being less than 70°.

19. A machine for polishing blades of aerofoil shape, comprising a carrier, a container for a polishing medium disposed adjacent the carrier, 30 the carrier and container being mounted for movement relative to each other, means mounted on the carrier for holding the blades in the polishing medium, means for translating the carrier and container relative to each other to pass 35 the blades in a continuous path through the polishing medium, means for changing, during the translation of the carrier relative to the container, the angles of the holding means relative to the direction of the said translation to vary 40 the angles of incidence of the blades between initial angles and limiting angles, and means in the container to elevate the particles of the polishing medium as the blades pass therethrough.
